ROCK DRILLING DEVICE

Elmer G. Gartin, Claremont, N. H., assignor to
 Sullivan Machinery Company, a corporation of
 Massachusetts

Application December 30, 1927, Serial No. 243,727
 Renewed February 11, 1932

20 Claims. (Cl. 121—26)

My invention relates to rock drilling devices and more particularly to fluid pressure operated percussive motors of the hammer drill type.

An object of my invention is to provide an improved pressure fluid operated motor. Another object of my invention is to provide an improved pressure fluid operated hammer drill of the valved type. A further object of my invention is to provide an improved drilling motor having an improved valve mechanism. A still further object of my invention is to provide an improved drilling motor having a coaxial relation of the distributing valve and rotation mechanism by means of which fluid distribution will be improved. Yet another object is to provide an improved pressure fluid motor having an improved valve mechanism of the compression-actuated type. Other objects and advantages of the invention will subsequently appear.

20 In the accompanying drawing I have shown for purposes of illustration one form which my invention may assume in practice.

In this drawing,—

Fig. 1 is a central longitudinal section, partially diagrammatic, showing the parts of the illustrative embodiment of the invention in one relative position.

Fig. 2 is a generally corresponding view showing parts in a different position.

30 The illustrative embodiment of the invention comprises a cylinder member 1 having a bore 2 in which a hammer piston 3 is reciprocable. The piston 3 is provided with a forwardly extending striking portion 4 having a splined connection with a nut 5 secured in the rear end of a chuck member 6 which also carries a bushing 7 in which a hollow rock drill steel 8 is supported for the hammering action of the hammer piston. The front end of the cylinder is closed by a buffer block 9 which is secured between the cylinder member 1 and the chuck housing member 10 in any suitable manner as, for example, by side rods one of which is shown at 11. The rear end of the cylinder bore 2 is closed by a member 12 which is traversed by longitudinal passages 13 and which has a rearwardly extending sleeve 14 formed integral therewith. To the rear of the bore 2 the cylinder member 1 is provided with an enlarged bore 16 which receives the member 12, the member 17, constituting a valve chest, the ratchet mechanism 18, and a forwardly projecting reduced portion 19 upon a rear head member 20. A cleansing fluid supply tube 21 is supported in a suitable manner in the rear head member 20 and extends through the various parts of the drill into the

rear end of the hollow drill steel 8. A throttle valve 22 is rotatably mounted in the rear head member 20 and controls the supply of motive fluid from a chamber 23 therein through a port 24 to a passage 25 which extends forwardly through the head member 20, through the ring 18 supporting the ratchet mechanism and through the valve chest member 17. A rifle bar 26 carrying at its rear end a pawl carrier 27 whose pawls engage with ratchet teeth 28 is rotatably mounted within the sleeve 14, and has a relatively long, smooth, cylindrical portion extending substantially throughout the full length of the sleeve and has a spirally rifled forward portion 29 cooperating with the rifle nut 30 carried within the rear end of the piston.

The hollow chest member 17 is provided with a bore generally designated 32 and comprising a rear portion of smaller diameter 33 and a forward portion of larger diameter 34. The inner wall of the chamber is formed by the periphery of the sleeve 14. The extreme rear end of the bore 33 is connected by a passage 35 with the fluid supply passage 25. Spaced forwardly from the passage 35 is an exhaust groove 36 communicating by a passage 37 with the atmosphere. Still further forward a peripheral groove 38 communicates with the smaller bore 32 and is connected by a passage 39 with the bore 2 of the cylinder at a point 40 adjacent the forward end of the cylinder. A port 41 communicates with the smaller bore 32 at a point near the forward end thereof serving to connect the bore with the fluid supply passage 25. A passage 43 communicates near the front end of the larger bore 34 with the latter and connects it with the longitudinally extending passage 25. A passage 44 similar to the passage 25 and having similar communication with the bores 33 and 34 serves to facilitate the fluid supply, this passage being connected by a groove 46 with the passage 25. A valve member 47 is provided arranged concentrically with the sleeve 14 and rifle bar 26 and having a larger head or spool 48 reciprocable in the larger bore 34 and a reduced sleeve-like portion 49 reciprocable in the reduced bore 33. This sleeve-like portion 49 has a peripheral groove 50 between its ends. Abutment portions 51 and 52 are formed at the opposite ends of the valve member for the purpose of limiting its movements in opposite directions, the abutment 51 stopping movement of the valve in the position in which the passage 43 is closed before permitting communication between the bore of the cylinder and a major portion of the surface of the forward end of the valve. 100 105 110

The abutment 52 permits fluid passing to the passage 35 to act upon the greater portion of the smaller end of the valve. A further passage 54 extends from a point at approximately the rear end of the larger bore 34 in the valve chest to a port 55 through the wall of the cylinder 2. Communication between the passage 54 and the larger bore 34 of the valve chest cannot be completely closed by the valve portion 48. A vent port 56 extends from a spaced point in the larger bore 34 to the atmosphere. The cylinder 1 is provided with exhaust port means 57 in a position to be overrun by the piston head near the end of its stroke in each direction.

The mode of operation of the mechanism described is self-evident. Assuming that the parts are initially in the position shown in Fig. 1, fluid supply through the valve 23 will pass by way of the passage 25 and the corresponding passage 44 through the passages 35 and 43 and the valve will remain in the position shown since the area at the forward end of the larger portion of the valve will exceed that subjected to the pressure through the passage 35. The fluid will accordingly flow through the ports 43 and 13 into the rear end of the bore of the cylinder and act upon the rear end of the piston, forcing the latter forward. At this time the front end of the cylinder bore is exhausted to atmosphere through port 40, passage 39, through the bore 33, past the groove 50 in the valve, through the annular groove 36 and thence through the lateral port 37 to atmosphere. When the piston 3 reaches a position in which the port 55 is uncovered, pressure fluid flows from the rear end of the cylinder bore through the passage 54 filling the space in the bore 34 to the rear of the larger portion or spool 48 of the valve 47 and as the pressure is flowing rapidly through the ports 43 and 13 it is substantially lower than the combined pressures acting on the rear areas of the spool 48 and sleeve-like portion 49. Therefore as the pressure acting on the rear areas of the valve is materially greater than the pressure acting on the front area of the valve, the latter will be thrown from the position shown in Fig. 1 to the position shown in Fig. 2. It will be noted that when the valve 47 is thrown into the position shown in Fig. 2 the enlarged portion or spool 48 enters the forward portion of the bore 34 thereby cutting off communication between the ports 43 and the ports 13. Upon further forward movement of the piston 3 the exhaust port 57 is opened thereby connecting the rear end of the cylinder bore with the atmosphere.

It will further be noted that when the valve is in the position shown in Fig. 2 pressure fluid flows from the supply passages 25, 44 through the lateral ports 41, through the bore 33, past the groove 50 in the valve, and thence through the passage 39 and port 40 to the forward end of the cylinder bore wherein the fluid acts upon the forward end of the piston forcing the latter rearwardly. At this time the rear end of the cylinder bore is exhausted to atmosphere through the exhaust port 57 while the pressure within the bore 34 at the rear of the spool 48 on the valve is vented to atmosphere through port 56. As the piston 3 continues its rearward movement the port 57 and port 55 are covered by the piston head. As the piston approaches the end of its rearward stroke the fluid trapped within the rear end of the cylinder bore 2 is highly compressed, the pressure acting on the forward area of the spool 48 building up until it overcomes the con-

stant pressure acting on the rearward area of the sleeve-like portion 49 of the valve. The valve 47 is then thrown rearwardly by compression from the position shown in Fig. 2 to the position shown in Fig. 1, the forward end of the cylinder bore again being connected with the fluid supply while the rear end of the cylinder bore is exhausted to atmosphere. The above cycle of events is repeated throughout the normal operation of the motor.

As a result of this invention an improved pressure fluid motor is provided wherein the power and efficiency of the motor is materially increased. It will further be noted that by arranging the distribution valve concentrically with the rotation mechanism the fluid distribution has been materially improved, it being possible by such an arrangement to place the supply passages so that the fluid will flow in a substantially straight path longitudinally of the motor directly into the rear end of the cylinder bore thereby increasing the power and speed of the working stroke of the hammer piston. It will still further be noted that by arranging the valve and rotation mechanism with the rear end of the cylinder in the novel manner described above it is possible to obtain access to these mechanisms without entirely dismantling the drilling motor, thereby facilitating replacements and repairs. Furthermore, by arranging the valve in the rear of and in axial alignment with the motor cylinder it has been made possible to throw the valve in one direction directly by compression built up in the rear end of the cylinder bore by the hammer piston. These and other advantages of the improved motor will be clearly apparent to those skilled in this art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a pressure fluid motor, a cylinder, a piston reciprocable therein, and fluid distribution means for supplying fluid to and exhausting fluid from said cylinder to effect reciprocation of said piston including a valve chest having a bore, a fluid supply passage communicating with one end of said bore, an exhaust passage communicating with said bore, a fluid conducting passage communicating with said bore at a point between the supply and exhaust passages for supplying fluid to the front end of the motor cylinder, a passage communicating with the valve chest bore between said fluid conducting passage and said supply passage and communicating with the cylinder, a valve reciprocably mounted in the valve chest bore for controlling said supply, exhaust and fluid conducting passages, and passage means for supplying fluid to the rear end of the cylinder and also controlled by said valve.

2. In a pressure fluid motor, a cylinder, a piston reciprocable therein, and fluid distribution means for supplying fluid to and exhausting fluid from said cylinder to effect reciprocation of said piston including a valve chest having a bore, a fluid supply passage communicating with one end of said bore, an exhaust passage communicating with said bore, a fluid conducting passage

- passage communicating with said bore at a point between the supply and exhaust passages for supplying fluid to the front end of the motor cylinder, a passage communicating with the valve chest bore between said fluid conducting passage and said supply passage and communicating with the cylinder, a valve reciprocably mounted in the valve chest bore for controlling said supply, exhaust and fluid conducting passages, a vent 5 passage controlled by said valve for connecting said last mentioned passage to atmosphere, and passage means for supplying fluid to the rear end of the cylinder and also controlled by said valve. 3. In a pressure fluid motor, a cylinder, a piston reciprocable therein, and fluid distribution means for supplying fluid to and exhausting fluid from said cylinder to effect reciprocation of said piston including a valve chest having a bore, a fluid supply passage communicating with one 10 end of said bore, an exhaust passage communicating with said bore, a fluid conducting passage communicating with the bore at a point between the supply and exhaust passages for supplying fluid to the front end of the motor cylinder, an additional supply passage communicating with the bore at a point between said last mentioned passage and said first mentioned supply 15 passage, a valve reciprocably mounted in the valve chest bore for controlling said passages, and a passage means for supplying fluid to the rear end of the cylinder and also controlled by said valve. 4. In a pressure fluid motor, a cylinder, a piston reciprocable therein, and fluid distribution means for supplying fluid to and exhausting fluid from said cylinder to effect reciprocation of said piston including a valve chest having a bore, a fluid supply passage communicating with said bore, an exhaust passage communicating with said bore, a fluid conducting passage communicating with the bore at a point between the supply and exhaust passages for supplying fluid to the front end of the motor cylinder, an additional supply passage communicating with the bore at a point between said last mentioned passage and said first mentioned supply passage, a passage communicating with the valve chest bore between said supply passages and communicating with the cylinder, a valve reciprocably mounted in the valve chest bore for controlling 20 25 30 35 40 45 50 55 60 65 70 75 said supply, exhaust and fluid conducting passages, and passage means for supplying fluid to the rear end of the cylinder and also controlled by said valve. 5. In a pressure fluid motor, a cylinder, a piston reciprocable therein, and fluid distribution means for supplying fluid to and exhausting fluid from said cylinder to effect reciprocation of said piston including a valve chest having a bore, a fluid supply passage communicating with said bore, an exhaust passage communicating with said bore, a fluid conducting passage communicating with the bore at a point between the supply and exhaust passages for supplying fluid to the front end of the motor cylinder, an additional supply passage communicating with the bore at a point between said last mentioned passage and said first mentioned supply passage, a passage communicating with the valve chest bore between said supply passages and communicating with the cylinder, a valve reciprocably mounted in the valve chest bore for controlling said supply, exhaust and fluid conducting passages, a vent passage controlled by the valve for connecting said last mentioned passage with the atmosphere, and passage means for supplying 80 85 90 95 100 105 110 115 120 125 130 135 140 145 150 fluid to the rear end of the cylinder and also controlled by said valve. 6. In a pressure fluid motor, a cylinder, a piston reciprocable therein, and fluid distribution means for supplying fluid to and exhausting fluid from said cylinder to effect reciprocation of said piston including a valve chest having a differential bore, passages communicating with the valve chest bore comprising an exhaust passage, a passage for conducting pressure fluid to the front end of the cylinder, a third passage leading to the cylinder for conducting pressure fluid from the cylinder to a pressure area on the valve to throw the latter, a fluid supply passage communicating with the valve chest bore at a point between said last mentioned passage and said second mentioned passage, and a differential valve in said valve chest bore for controlling said exhaust, fluid conducting and supply passages. 7. In a pressure fluid motor, a cylinder, a piston reciprocable therein, and fluid distribution means for supplying fluid to and exhausting fluid from said cylinder to effect reciprocation of said piston including a valve chest having a differential bore, passages communicating with the valve chest bore comprising an exhaust passage, a passage for conducting pressure fluid to the front end of the cylinder, a third passage leading to the cylinder for conducting pressure fluid from the cylinder to a pressure area on the valve to throw the latter, a fluid supply passage communicating with the valve chest bore at a point between said last mentioned passage and said second mentioned passage, a differential valve in said valve chest bore for controlling said exhaust, fluid conducting and supply passages, and a passage controlled by the valve for venting said third passage to atmosphere. 8. In a pressure fluid motor, a cylinder, a piston reciprocable therein, and fluid distribution means for supplying fluid to and exhausting fluid from said cylinder to effect reciprocation of said piston including a valve chest having a differential bore, passages communicating with the valve chest bore comprising an exhaust passage, a passage for conducting pressure fluid to the front end of the cylinder, a third passage leading to the cylinder for conducting pressure fluid from the cylinder to a pressure area on the valve to throw the latter, a fluid supply passage communicating with the valve chest bore at a point between said last mentioned passage and said second mentioned passage, a differential valve in said valve chest bore for controlling said exhaust, fluid conducting and supply passages, a passage controlled by the valve for venting said third passage to atmosphere, and passage means also controlled by said valve for supplying pressure fluid to the rear end of the cylinder. 9. In a pressure fluid motor, a cylinder, a piston reciprocable therein, and fluid distribution means for supplying fluid to and exhausting fluid from said cylinder to effect reciprocation of said piston including a valve chest having a differential bore, a differential valve reciprocably mounted in the valve chest bore and having an elongated sleeve-like body portion fitting the smaller bore and an enlarged end spool fitting the larger bore, said sleeve-like portion having a peripheral groove between its ends, a supply passage communicating with the larger bore, and three passages communicating with the smaller bore, one leading to the cylinder, the second to the fluid supply, and the third to exhaust, the groove in the sleeve-like portion of said valve, upon reciprocation of the

valve, connecting alternatively the passage leading to the cylinder with the supply and exhaust passages.

10. In a pressure fluid motor, a cylinder, a piston reciprocable therein, and fluid distribution means for supplying fluid to and exhausting fluid from said cylinder to effect reciprocation of said piston including a valve chest having a differential bore, a differential valve reciprocably mounted in the valve chest bore and having an elongated sleeve-like body portion fitting the smaller bore and an enlarged end spool fitting the larger bore, said sleeve-like portion having a peripheral groove between its ends, a supply passage communicating with the larger bore, another supply passage communicating with the smaller bore, two other passages communicating with the smaller bore and a third with the larger bore, two of said last mentioned passages leading to the cylinder and the third to exhaust, the groove in the sleeve-like portion of said valve, upon reciprocation of the valve, connecting alternatively one of the passages leading to the cylinder with the second mentioned supply and the exhaust passages, and a vent passage controlled by said valve and communicating with the larger bore for connecting said other passage leading to the cylinder to atmosphere.

11. In a pressure fluid motor, a cylinder, a piston reciprocable therein, and fluid distribution means for supplying fluid to and exhausting fluid from said cylinder to effect reciprocation of said piston including a valve chest having a differential bore, a differential valve reciprocably mounted in the valve chest bore and having an elongated sleeve-like body portion fitting the smaller bore and an enlarged end spool fitting the larger bore, said sleeve-like portion having a peripheral groove between its ends, a supply passage communicating with the larger bore, another supply passage communicating with the smaller bore, two other passages communicating with the smaller bore and a third with the larger bore, two of said last mentioned passages leading to the cylinder and the third to exhaust, the groove in the sleeve-like portion of said valve, upon reciprocation of the valve, connecting alternatively one of the passages leading to the cylinder with the second mentioned supply and the exhaust passages, a vent passage controlled by said valve and communicating with the larger bore for connecting said other passage leading to the cylinder to atmosphere, and a passage also controlled by the valve for connecting the larger bore with the rear end of the cylinder.

12. In a pressure fluid motor, a cylinder, a piston reciprocable therein, and fluid distribution means for supplying fluid to and exhausting fluid from said cylinder to effect reciprocation of said piston including a valve chest having a differential bore, a differential valve reciprocably mounted in the valve chest bore and having an elongated sleeve-like body portion fitting the smaller bore and an enlarged end spool fitting the larger bore, said sleeve-like portion having a peripheral groove between its ends, a supply passage communicating with the larger bore, two passages communicating with the smaller bore and a third with the larger bore, two of said last mentioned passages leading to the cylinder and the third to exhaust, another supply passage leading to the smaller bore, the groove in the sleeve-like portion of said valve, upon reciprocation of the valve, connecting alternatively one of the passages leading to the cylinder with the last mentioned supply and the exhaust passages, a vent passage con-

trolled by said valve and communicating with the larger bore for connecting said other passage leading to the cylinder to atmosphere, a passage also controlled by the valve for connecting the larger bore with the rear end of the cylinder, and a passage for constantly supplying fluid to an end of the sleeve-like portion of said valve.

13. In a pressure fluid motor, a cylinder, a piston reciprocable therein, and fluid distribution means for supplying fluid to and exhausting fluid from said cylinder to effect reciprocation of said piston including a valve chest having a differential bore having closed ends, a differential valve reciprocably mounted in the valve chest bore and having a sleeve-like body portion fitting the smaller bore and an enlarged end spool fitting the larger bore, a passage for supplying fluid constantly to one end of the smaller bore to act on one end of the sleeve-like body portion of the valve, three passages communicating with the smaller bore, one an exhaust passage, another a fluid supply passage, and the third a passage communicating with the smaller bore between said exhaust and fluid supply passages and leading to the forward end of the cylinder, two passages communicating with the larger bore, one a supply passage and the other leading to the cylinder, fluid flow through said passages being controlled by said valve and a third passage communicating with the larger bore and leading to the cylinder. 105

14. In a pressure fluid motor, a cylinder, a piston reciprocable therein, and fluid distribution means for supplying fluid to and exhausting fluid from said cylinder to effect reciprocation of said piston including a valve chest having a differential bore having closed ends, a differential valve reciprocably mounted in the valve chest bore and having a sleeve-like body portion fitting the smaller bore and an enlarged end spool fitting the larger bore, a passage for supplying fluid constantly to one end of the smaller bore to act on one end of the sleeve-like body portion of the valve, three passages communicating with the smaller bore, one an exhaust passage, another a fluid supply passage, and the third a passage communicating with the smaller bore between said exhaust and fluid supply passages and leading to the forward end of the cylinder, two passages communicating with the larger bore, one a supply passage and the other leading to the cylinder, fluid flow through said passages being controlled by said valve, a third passage communicating with the larger bore and leading to the cylinder, a passage communicating with the larger bore for venting one of the passages leading to the cylinder to atmosphere and also controlled by the valve. 110

15. In a pressure fluid motor, a cylinder, a piston reciprocable therein, and fluid distribution means for supplying pressure fluid to and exhausting fluid from said cylinder to effect reciprocation of said piston including a valve chest having a differential bore, a differential hollow sleeve valve reciprocably mounted in the valve chest bore and having an enlarged flange fitting the larger bore and an elongated imperforate sleeve-like body portion fitting the smaller bore, said valve having pressure areas the action upon each of which of pressure fluid produces a pressure acting longitudinally of said valve, said pressure areas all being formed either upon an end or upon the outside of said valve, passages for conducting pressure fluid to said areas for positioning said valve including a passage communicating with the larger bore at the rear side 150

5 of said flange for conducting pressure fluid from the motor cylinder to the rear pressure area on said flange to throw said valve forwardly, a fluid conducting passage communicating with said 10 valve chest bore and leading to the forward end of the motor cylinder, an exhaust passage communicating with said valve chest bore, a fluid supply passage communicating with said valve chest bore, and a fluid conducting passage communicating with said valve chest bore and leading to the rear end of the motor cylinder, said valve controlling the supply of pressure fluid through said fluid conducting passages to the opposite ends of said motor cylinder and the exhaust from the forward end of said motor cylinder, and said valve being thrown into its rearward position by compression pressure built up in the rear end of the cylinder during the rearward piston stroke and acting on the forward pressure area on the forward end of said valve. 15

20 16. In a pressure fluid motor, a cylinder, a piston reciprocable therein, and fluid distribution means for supplying pressure fluid to and exhausting fluid from said cylinder to effect reciprocation of said piston including a valve chest having a differential bore, a differential hollow sleeve valve reciprocably mounted in the valve chest bore and having an enlarged flange fitting the larger bore and an elongated imperforate sleeve-like body portion fitting the smaller bore, said valve having pressure areas, passages for conducting pressure fluid to said areas for positioning said valve including a passage communicating with the larger bore at the rear side of said flange for conducting pressure fluid from the motor cylinder to the rear pressure area on said flange to throw said valve forwardly, said valve positioning means also including a passage for supplying pressure fluid from the source of fluid supply to a rearward pressure area on the valve for constantly urging the valve toward its forward position, a fluid conducting passage communicating with said valve chest bore and leading to the forward end of the motor cylinder, an exhaust passage communicating with said valve chest bore, a fluid supply passage communicating with said valve chest bore, and a fluid conducting passage communicating with said valve chest bore and leading to the rear end of the motor cylinder, said valve controlling the supply of pressure fluid through said fluid conducting passages to the opposite ends of said motor cylinder and the exhaust from the forward end of said motor cylinder, and said valve being thrown into its rearward position by compression pressure built up in the rear end of the cylinder during the rearward piston stroke and acting on the forward pressure area on the forward end of said valve. 25

30 17. In a pressure fluid motor, a cylinder, a piston reciprocable therein, and fluid distribution means for supplying pressure fluid to and exhausting fluid from said cylinder to effect reciprocation of said piston including a valve chest having a differential bore, a differential hollow sleeve valve reciprocably mounted in the valve chest bore and having an enlarged flange fitting the larger bore and an elongated imperforate sleeve-like body portion fitting the smaller bore, said valve having pressure areas, passages for conducting pressure fluid to said areas for positioning said valve including a passage communicating with the larger bore at the rear side of said flange for conducting pressure fluid from the motor cylinder to the rear pressure area on said flange to throw said valve forwardly, a fluid conducting passage communicating with said valve chest bore, and a fluid supply passage communicating with said valve chest bore, and a fluid conducting passage communicating with said valve chest bore and leading to the forward end of the motor cylinder, an exhaust passage communicating with said valve chest bore, a fluid supply passage communicating with said valve chest bore, and a fluid conducting passage communicating with said valve chest bore and leading to the rear end of the motor cylinder, said valve controlling the supply of pressure fluid through said fluid conducting passages to the opposite ends of said motor cylinder and the exhaust from the forward end of said motor cylinder, and said valve being thrown into its rearward position by compression pressure built up in the rear end of the cylinder during the rearward piston stroke and acting on a forwardly facing area on said valve. 35

40 18. In a pressure fluid motor, a cylinder, a piston reciprocable therein, and fluid distribution means for supplying pressure fluid to and exhausting fluid from said cylinder to effect reciprocation of said piston including a valve chest having a differential bore, a differential hollow sleeve valve reciprocably mounted in the valve chest bore and having an enlarged flange fitting the larger bore and an elongated imperforate sleeve-like body portion fitting the smaller bore, said valve having pressure areas the action upon each of which of pressure fluid produces a pressure acting longitudinally of said valve, passages for conducting pressure fluid to said areas for positioning said valve including a passage communicating with the larger bore at the rear side of said flange for conducting pressure fluid from the motor cylinder to the rear pressure area on said flange to throw said valve forwardly and a passage constantly supplied with live pressure during running of said motor and communicating with said valve chest bore at a point in the latter spaced from and further to the rear than the point of communication of said last mentioned passage, to provide a forward bias to said valve, a fluid conducting passage communicating with said valve chest bore and leading to the forward end of the motor cylinder, an exhaust passage communicating with said valve chest bore, a fluid supply passage communicating with said valve chest bore, and a fluid conducting passage communicating with said valve chest bore and leading to the rear end of the motor cylinder, said valve controlling the supply of pressure fluid through said fluid conducting passages to the opposite ends of said motor cylinder and the exhaust from the forward end of said motor cylinder, and said valve being thrown into its rearward position by compression pressure built up in the rear end of the cylinder during the rearward piston stroke and acting on a forwardly facing area on said valve. 45

50 19. In a rock drill, a pressure fluid actuated percussive motor comprising a cylinder, a piston reciprocable therein, fluid distribution means for said motor including a valve chest in longitudinal alignment with said cylinder, a tubular valve reciprocable longitudinally in said valve chest and comprising an imperforate sleeve open from end to end, said valve having an area in constant communication with the rear end of the cylinder whereby the valve is thrown in the rearward direction by compression pressure built up in the 55

55

60

rear end of the cylinder on the return stroke of the piston, means for throwing the valve in the opposite direction comprising an annular shoulder on said valve presenting a rearwardly facing area, 5 means for subjecting the latter area to intermittent pressure, and means for subjecting a second rearwardly facing area on the exterior of said valve to constant pressure.

20. A pressure fluid motor comprising a cylinder, a piston reciprocable therein, fluid distribution means for effecting reciprocation of said piston comprising a valve chest in longitudinal alinement with said cylinder, a reciprocable dif-

ferential valve in said valve chest and comprising an imperforate sleeve open from end to end, said valve having an area in constant communication with the rear end of the cylinder whereby the valve may be thrown rearwardly by compression of the fluid which is trapped in the rear end of the cylinder at the time of closing of the exhaust, and means for throwing the valve in the opposite direction including a rearwardly facing area adapted to be subjected to intermittent pressure and an area disposed rearwardly of the latter area and subjected to constant fluid pressure. 80 85
